UNITED STATES PATENT OFFICE.

DANIEL W. SMITH, OF ST. LOUIS, MISSOURI, ASSIGNOR OF ONE-HALF TO
JOSEPH C. ADDINGTON, OF SAME PLACE.

STEAM-GENERATOR.

SPECIFICATION forming part of Letters Patent No. 399,165, dated March 5, 1889.

Application filed November 26, 1887. Serial No. 256,245. (No model.)

To all whom it may concern:

Be it known that I, DANIEL W. SMITH, a citizen of the United States, residing at the city of St. Louis, in the State of Missouri, have invented a certain new and useful Improvement in Steam-Generators, of which the following is a full, clear, and exact description, reference being had to the accompanying drawings, forming part of this specification, and in which—

Figure 1 is a side elevation of my improved generator. Fig. 2 is a top or plan view. Fig. 3 is a vertical section through the upper series of boilers or heating-tanks, this section being taken on line 3 3, Fig. 2. Fig. 4 is a similar view of the lower series of boilers or heating-tanks, the section being taken on line 4 4, Fig. 2. Fig. 5 is an enlarged vertical section through one of the burners. Fig. 6 is an enlarged detail section of one of the automatic valves. Fig. 7 is an enlarged view illustrating a modified form of burner for heating the tanks. Fig. 8 is a section through the valve-operating device, the section being taken on line 8 8, Fig. 1. Fig. 9 is a vertical section through the main steam boiler or receiver and the boilers, taken on line 9 9, Fig. 2. Fig. 10 is a horizontal section through the upper series of heating-tanks, taken on line 10 10, Fig. 1. Fig. 11 is a view showing the exhaust-pipe from the engine connected with a pump for forcing the exhaust into the boiler.

My invention relates to certain improvements in steam-generators; and my invention consists in features of novelty, hereinafter fully described, and pointed out in the claims.

Referring to the drawings, A represents a steam drum or receiver, with which communicates a main steam-pipe, A', leading to one or more engines or motors. An exhausting-pipe, 1, from the engine leads the exhaust-steam to a suitable force-pump, 2, operated by any suitable connection with the engine. This pump forces the exhaust into the pipe 3, which has secured to it a head, B, as shown in Fig. 1. With this head connects a steam-pipe, C, a steam-pipe, D, and a number of smaller steam-pipes, E. The steam-pipe C passes upward from the head B and communicates indirectly with a drum, F, located upon the receiver A, said drum communicat-

ing with the interior of the receiver by means of a short pipe, F', provided with a valve, F².

The pipe D extends in a horizontal direction and enters a boiler, G, as shown in Figs. 55 1 and 2. This pipe is provided with a valve, D', which will automatically close against back-pressure, preventing the return of the exhaust-steam, which is forced into the boiler G by means of the said pump 1 from the exhaust-steam pipe through the pipe D, as indicated by arrows in Fig. 4.

The boiler G is connected at or near its bottom with a similar boiler, H, by means of pipes G' and H'. The pipe G' is provided with an automatic valve, G², outside the pipe H', and within the pipe it is provided with a ball-valve, G³, these valves acting to check the return of water or steam from the boiler H to the boiler G. The boiler G is connected 70 with the boiler H at or near its upper end by means of like pipes H' and G', which in this case are also provided with the valves G¹ H², respectively.

The tank or boiler H and a similar boiler, 75 I, communicate with each other at or near their bottoms by a pipe, I', and at or near their upper ends by a pipe, I². The pipe I² extends into the boiler H and also into the boiler I. Within the boiler H it is provided with a flaring end, as shown in Fig. 4, and into this flaring end the steam from the inner end of the pipe H' is forced, causing, as it enters, an increase of pressure in the boiler H, which causes the steam to pass through the pipe I² 85 into the boiler I. From the pipe I² the steam is made to pass through a pipe, J², which is made in the same form as the pipe I², and whose flaring end is located with relation to the end of the pipe I² the same as above described in speaking of the flaring end of the pipe I² and the end of the pipe H'.

J is another boiler, similar to the boilers I, and G, H, connected to the former by means of the injector or nozzle J², and which is connected at or near its lower end with the boiler I by a pipe, J', for the passage of the water, and which is connected at or near its upper end to the boiler I by the pipe J², as above stated, and in like manner the boiler J communicates with another and similar boiler, K, at top and bottom by pipes K' and K², the

pipe K² being formed the same as those J' I' and discharging into a pipe, L², which takes steam from the boiler K and delivers it into a boiler, L, and in like manner the boiler K is also connected by a lower pipe, L', to the boiler L, which in turn is connected by similar pipes, M' M², at bottom and top, respectively, to a boiler, M, and this latter boiler communicates, by means of pipes A², with the main

10 steam drum or receiver A, as shown in Fig. 9.

Now it will be seen that by forcing the exhaust-steam into the boiler G the pressure in this boiler will be raised until it is equal to that in the remaining boilers of the series, 15 and when it becomes greater than this latter pressure the valves G² will be forced open and steam and water will circulate through the series of boilers until the pressure is again balanced throughout the same. The steam 20 and water as they pass from boiler to boiler will take the course indicated by the feathered and featherless arrows respectively.

To heat the steam in the various boilers just described, I form in their lower parts 25 heating-chambers N, within which are located burners N'. These are preferably electric burners, as shown in Fig. 5, preferably each provided with two platirniums to increase their capacity. N' represents the wires of the burners. As the steam passes from one of these 30 boilers to another, it is heated and superheated and the water in the boilers is heated, generating steam, which is eventually discharged into the main receiver A.

35 The form of valve G² is illustrated in Fig. 6, being simply a ball fitting and held within the flaring end of the pipe G' by means of a cage or cross-wires G¹.

The receiver A is preferably provided with 40 a mud-drum, A²², provided with a blow-off valve, A²³. The receiver is also preferably provided with a kettle, A⁴, having a valve, A²⁰, which acts to collect condensed steam and carry it through a pipe, A⁵, having a valve, A²¹, into a boiler, A⁶, which also connects with the receiver A by means of an injector-pipe, A⁷, or pipe having an injector-nozzle. This boiler A⁶ is also provided with a heating-chamber, A⁸, and a burner, A⁹, and it may be 45 connected to a similar boiler, A¹⁰, by a pipe, A¹¹, and the boiler A¹⁰ may be again connected by a pipe, A¹², to the pipe H', as shown at A¹³, Fig. 4.

50 Communicating with the main steam-pipe D, by means of a pipe, P', is a water-tank, P, from which the heating-tanks are supplied with water. The pipe P' is provided with a butterfly-valve, P², having a crank or arm, P³, on its outer end, (see Fig. 8,) to which is connected a cord, P⁴, leading to an automatic cut-off, P⁵, (see Fig. 1,) with which the wires of the burners connect, as is shown, described, and claimed in my application filed herewith, Serial No. 256,243, and to that application reference is made for a full description of the cut-off. In this application A' represents the

steam-pipe B of my other application, to which the piston arrangement is connected and which leads from the boiler.

Supported on a frame, U, is an upper series 70 of boilers, U' U² U³ U⁴ U⁵, provided with chambers U⁶, in which the burners U⁷, like those of the lower boilers, are located. These boilers are connected together and to the drum F on the receiver by injector-pipes U⁹, similar 75 to pipes I I² J², &c., of the lower boilers, and they are supplied with water, as shown in Fig. 3, and act to generate steam which enters the receiver through the drum F. The circulation of the steam is indicated by arrows in 80 Fig. 10. The exhaust-steam pipe C connects with two of these boilers, it having a branch marked C⁴, (see Fig. 10,) and thus indirectly connects with the drum F, as stated. One of the boilers, U³, may, by a branch, U¹⁰, connect with the steam-pipe A', and this steam from these boilers may be taken direct to the engine or other motor.

Steam may be discharged into the water-tank P from the receiver A, to heat the water, 90 through a pipe, V.

A pipe, W, may connect the exhaust-steam pipe or head B with the pipe I², (see Fig. 4,) to assist in starting the partial vacuum in the first boiler.

95 The pipes E discharge exhaust-steam into the boilers to assist in heating the water.

I claim as my invention—

1. In combination with a number of boilers and a receiver to which the boilers are connected, pipes connecting the boilers and having flared ends and injector-nozzles adapted to inject therein arranged above the water-level, and burners for heating the water in the boilers, substantially as set forth. 100

2. The combination, with a number of boilers and a receiver to which said boilers are connected, of pipes connecting said boilers, each having a flared mouth and an injector-nozzle, and said mouths and nozzles being arranged opposite each other and above the water-level within said boilers, water-pipes connecting the boilers at their lower parts, and burners for heating the water in said boilers, substantially as set forth. 110

3. In combination with a number of boilers provided with burners and a receiver to which the boilers are connected, injector-pipes connecting the boilers near their upper parts, pipes connecting the boilers near their lower parts, one of which is provided with automatic valves, and the steam-exhaust pipes for discharging steam into the boilers, substantially as and for the purpose set forth. 120

4. In combination with a number of boilers 125 provided with burners and a receiver to which the boilers are connected, injector-pipes connecting the boilers together near their upper parts, pipes connecting the boilers near their lower parts, exhaust-pipe provided with an automatic valve discharging steam into the tanks, and a water-tank provided with auto-

matic valve and connected with the exhaust-steam pipe, substantially as shown and described.

5. In combination with a number of boilers provided with burners and a receiver to which the boilers are connected, injector-pipes connecting the boilers near their upper parts, pipes connecting the boilers near their lower parts, and exhaust-steam pipe discharging steam into the boilers and pipes, substantially as and for the purpose set forth.

6. In combination with a lower series of boilers provided with burners and a receiver to which said boilers are connected, an upper series of boilers connected to the receiver and provided with injector-pipes, substantially as and for the purpose set forth.

7. In combination with an upper and lower series of boilers provided with heaters and a receiver to which said boilers are connected, a kettle arranged in the receiver, substantially as shown and described, for the purpose set forth.

8. In combination with a series of boilers provided with heaters and a receiver to which the boilers are connected, an exhaust-steam pipe discharging steam into the boilers through a pipe, B, and pipe E, connecting the exhaust-steam pipe to the respective boilers, substantially as and for the purpose set forth.

DANIEL W. SMITH.
